his Attorney.

UNITED STATES PATENT OFFICE.

FERDINAND W. BEARD, OF YOUNTVILLE, CALIFORNIA.

BOTTLE-OPENER.

1,106,862.

Specification of Letters Patent.

Patented Aug. 11, 1914.

Application filed October 4, 1912. Serial No. 723,938.

To all whom it may concern:

Be it known that I, FERDINAND W. BEARD, a citizen of the United States, residing at Yountville, in the county of Napa and State 5 of California, have invented new and useful Improvements in Bottle-Openers, of which the following is a specification.

My invention has special relation to the class of bottle opening devices and more 10 particularly to an opening device which is permanently carried by the bottle cap.

It will be realized that serious inconvenience is caused by the inability to open ordinary beer bottles and the like in many instances, the person being without an opener.

It is my object to provide a simple, durable, yet efficient device which is normally carried upon the cap of the bottle whereby the operator may remove the latter therefrom 20 whenever occasion requires.

With the above and other objects in view, my invention relates to such details of construction and in the arrangement and combination of the several parts as will be hereinafter fully described and specifically pointed out in the appended claims.

In describing my invention in detail, reference will be had to the accompanying drawings wherein like characters denote like 30 or corresponding parts throughout the several views, and in which:

Figure 1 is a side elevation of the top of the neck of the bottle showing my invention in connection with the cap thereof. Fig. 2 35 is a side elevation of the modified form of opener, and Fig. 3 is still another modified form of opener.

In the accompanying drawings wherein is illustrated the preferred form of my invention, the numeral 10 designates the fragmentary portion of the bottle neck upon the upper extremity of which is situated an ordinary crimped top 11. While I have illustrated this form of top in connection with 45 my invention, it is apparent that the latter can be employed in connection with other forms as well and that its operation is not effected materially if a substitution should be used.

50 In the preferred form of my invention, a cap is provided with a lug 12 having its under face disposed substantially horizontal as shown at 13, this being for the purpose that will be hereinafter set forth. A pair of ears 55 14 are carried by the cap which have journaled therethrough a pintle 15, the latter

supporting an arm 16 which normally lies substantially parallel with the neck. When the cap is to be removed from the bottle, the arm is drawn into position shown in dotted lines, so that it engages the under face of the latter and when pressure is applied to the outer extremity thereof, the cap will be slowly but surely unseated.

It will be apparent that the provision of my invention upon the cap does not affect the cost of the same materially and that it is very simple in construction whereby it can be manufactured separately at a minimum cost.

70 In Fig. 2 I have illustrated another form of opening device which consists of an arm 17 having an intermediate portion thereof curved to form rods 18 at substantially right angles thereto, and pivoted upon the cap 75 through the medium of a pintle 19 acting in co-operation with ears 20. When the arm is moved into position shown in dotted lines, the innermost of the rods 18 will engage sides of the cap whereby when pressure is 80 applied to the arm, the cap will be unseated. This form is also very simple and in operation works very efficiently.

Fig. 3 discloses another form of my invention which is in the form of a substantially L shaped arm 21 pivoted upon the cap 85 through the medium of a pintle 22 and ears 23, the forward extremity 24 in the arm engaging side of the cap so that the aperture may force the latter over the side. This 90 form appears to be the simplest of all and it is apparent that while it is characterized by the elements of simplicity, its operation is performed in an efficient manner.

I desire to lay the greatest of stress upon 95 the simplicity of each part of my invention and it is thought that the advantages and novel features of the same will be readily deduced from the foregoing description.

I desire it to be understood that I may 100 make slight changes in the construction and in the arrangement and combination of the several parts, provided, however, such changes fall within the scope of the subjoined claims.

Having thus fully described my invention, what I claim as new and desire to secure by Letters Patent, is:

1. In a crown cap removing device for bottles, a crown cap, a lever pivoted to said cap and having a stop portion for engagement with the cap to limit movement of the

lever upon stress applied thereto in an upward direction with respect to the bottle, for removing said cap, substantially as described.

5 2. In a crown cap removing device for bottles, a cap structure and a lever structure movably mounted on the cap structure, one of said structures having a stop limiting movement of the lever structure in an upward direction for lifting the cap off from the bottle, substantially as described.

10 3. In a crown cap removing device for bottles, a crown cap having a flange over-

hanging the mouth of the bottle, a lever pivoted to the overhanging flange and provided 15 with a stop portion for engagement against the overhanging flange of the cap to limit movement of the lever upon stress applied thereto in an upward direction with respect to the bottle to lift the cap off from the 20 latter, substantially as described.

FERDINAND W. BEARD.
